(57) CLAIM

The ornamental design for a timed monthly appointment leaf, as shown and described.

DESCRIPTION

FIG. 1 is a plan view of the page layout for a new and ornamental design for a timed monthly appointment leaf; FIG. 2 is an enlarged plan view of the left portion thereof; and,

FIG. 3 is an enlarged plan view of the right portion thereof. Portions of indicia are shown in phantom for environmental purposes only and forming no part of the claimed invention.
